UNITED STATES PATENT OFFICE.

ALANSON McD. GRAY, OF ELIZABETH, NEW JERSEY.

COOLING-MACHINE.

1,286,880.

Specification of Letters Patent.

Patented Dec. 3, 1918.

Application filed March 6, 1917. Serial No. 152,917.

To all whom it may concern:

Be it known that I, ALANSON McD. GRAY, a citizen of the United States, residing at 22 Hazard Place, Elizabeth, New Jersey, have invented certain new and useful Improvements in Cooling-Machines, of which the following is a clear, full, and exact description.

My invention relates to improvements in oil cooling machines and is more particularly designed as an improvement of the apparatus for separating wax from paraffin oil, disclosed in Patent No. 660,251 of October 3, 1899, to P. R. Gray.

In the chilling machine therein described, there is provided a series of cooling vessels, the bottom of each vessel being connected to the top of the next vessel in the series by a suitable pipe. Each vessel is provided with a water or brine jacket, the jackets of the respective vessels being also connected. Pumping means is provided to deliver oil distillate to the top of the first vessel and to force it through the series of vessels, from the bottom of the last one of which it is discharged. A cooling medium, such as water, brine, or ammonia gas, is at the same time pumped through the jackets in the opposite direction. As the distillate is cooled, paraffin wax is deposited on the inner walls of the vessel and to remove this, each vessel is equipped with a rotary frame having small scraper elements so mounted thereon as to be thrown against the inner wall of the vessel by centrifugal force when the frame is rotated.

Such an arrangement as shown in the patent above referred to is satisfactory when dealing with light distillates. The purpose of my invention is to provide a machine of this type that is better suited for the treatment of heavy distillates.

On account of the greater density of heavy distillates, the rotary scraper frames in the vessels encounter greater resistance and must therefore be run at a lower speed than when the lighter distillates are being treated. It is also often desirable, in order to reduce the floor space occupied, as well as to bring the cooling medium in the jackets closer to the central portion of the contents of the vessels and to minimize the danger of col-

lapse of the walls of the vessels because of the pressure of the cooling medium in the jackets, to reduce the diameters of the cooling vessels. These factors result in such a reduction of the peripheral speed of the scraper frame that the scraper elements carried thereby are not subjected to sufficient centrifugal force to hold them effectively against the inner wall of the vessel. Moreover, the deposit on the inner walls of the vessels is much thicker and denser when the heavy distillate is treated, and there is consequently a tendency on the part of the loosely pivoted scraper elements to ride over a portion of the deposit. It is therefore an object of my invention to provide improved means for holding the scraper elements positively against the inner walls of the vessels.

As it would be impracticable to force a heavy distillate into the first vessel of the series under sufficient pressure to carry it past the frames in the successive vessels and through the pipes between them, especially where the vessels, being reduced in diameter, afford a more restricted passageway, it is a further object of my invention to provide means for assisting the supply pump by acting on the distillate between each pair of vessels, whereby it need not be introduced into any vessel at a higher pressure than that necessary to carry it through that vessel. It is also an object of my invention to so arrange these means that they may be independently and quickly removed for the purpose of repair, cleaning, or the like.

While my invention is particularly adapted for use in connection with the chilling of heavy oil distillates, it is to be understood that its advantages are by no means limited to that field, but that it is also applicable to the cooling of light distillates, as well as to other substances whose treatment involves their passage through a series of vessels whether for cooling or for other purposes.

In the drawings,
Figure 1 is a view in elevation of a series of cooling vessels;

Fig. 2 is an end view of the arrangement in Fig. 1;

Figs. 3 and 4 are enlarged detail views

with parts broken away to more clearly show the screw-conveyer and scrapers;

Fig. 5 shows the arrangement for automatically returning insufficient cooled distillate to the cooling vessels;

Fig. 6 shows a detail view of the thermostat in cross-section; and

Figs. 7 and 8 show a modified mounting for the scrapers carried by the rotary shaft.

10 Each cooling vessel comprises a cylindrical body member 2, having an inner wall 4 and an outer wall 6, the space between the inner and outer walls forming a jacket for the reception of the cooling medium. The

15 jackets of adjacent vessels are connected by conduits 7, the conduits between succeeding pairs of vessels being arranged at opposite ends of the vessel common to both pairs, so that the cooling fluid is forced

20 to pass throughout the length of each jacket. Each cooling vessel is provided with a lower head 8, having supporting feet 10 thereon, and is also provided with an upper head 12 on which are upstanding brackets 14 sup-

25 porting a frame 16. Alined bearings 18, 20 and 22 are provided in frame 16, upper head 12 and lower head 8 respectively (see Figs. 1 and 4). The vertical scraper shaft 24 extends through these bearings, being

30 supported at its lower end on plate 26 carried by the lower head. The upper end of the shaft is provided with a beveled gear wheel 28, arranged to mesh with a beveled

35 spur wheel 30 on the horizontal shaft 32, carried in a bracket 33 supported on the frame 16. This shaft has tight and loose pulleys 4 and 6 respectively, whereby the shaft may be driven by a belt. Although

40 I have shown each cooling vessel provided with separate shaft and tight and loose pulleys, this is not essential; the use of an individual driving means for each shaft, however,

45 is sometimes advantageous in case it is desired to rotate only a portion of the scraper shafts on account of injury to the mechanism carried by the remaining scraper shafts. Each scraper shaft carries a frame

48 secured thereon and provided with a plurality of scrapers 40. These scrapers

50 are of the same general type as those described in the above mentioned patent, and are pivotally mounted on the frame by means of the lugs 42 on the frame and lugs 44 on each scraper, pivotally connected by

55 the rod 46. In the improved arrangement I mount a coil spring 48 around the rod, one end of the spring being attached to a lug 42 on the frame, the opposite end being secured to one of the lugs 44 on the scraper, the arrangement of parts being such that the

spring tends to force the scraper against the inner wall of the cooling vessel. The action of the spring thus supplements the centrifugal force, due to the rotation of the scraper frame, and insures that the scrapers

will be forced outwardly with sufficient force to scrape all the deposit off the inner wall of the vessel.

Each lower and upper head 8 and 12 is provided with an eccentric, inwardly concave portion 50, communicating with which is a lateral cylindrical extension 52 open at both ends and provided at one end with a flange 54, by which it may be secured to a corresponding portion on the head of an adjacent cooling vessel to form a conduit connecting the vessels. In this conduit is mounted a shaft 58 carrying a screw-conveyer 60. The shaft has collars 62 adjacent its opposite ends which bear against the cylinder heads 63 closing the outer ends of the conduit; each conduit head is provided with packing 64 and a gland 66.

As will be seen from the drawings, the conduits between successive pairs of vessels are at opposite ends of the vessel common to both pairs, thus providing that distillate shall be passed through the entire length of each cooling vessel. The cylindrical extensions 52 are offset laterally from the axes 90

of the cylindrical body members 2, and in setting up a battery of the cooling vessels the conduits at the upper and lower ends of the vessel respectively are divided into two groups, the conduits of one group having 95

their axes at one side of the vertical axes of the cooling vessels, and the conduits of the other group having their axes at the opposite side of the vertical axes of the cooling vessels. This is clearly shown in Figs. 1 and 100

2. By this arrangement it is possible to withdraw any one of the shafts 58, together with its screw-conveyer, without disturbing any of the other shafts 58. In general, suc-

cessive conduits at the upper or lower ends 105

of the vessels will be arranged on opposite sides of the vertical axes of the vessels, but as shown in the lower right-hand portion of Fig. 1 of the drawing, two adjacent conduits

may be placed in alinement on the same side 110

of the vertical axes of their respective vessels, a single shaft being used for both conduits and being withdrawn through the end of one of them. Each shaft 58 is provided

115 with a sprocket 68. The sprockets 68 on the shafts in the upper conduits are directly connected by chains 70 to sprockets 72 on the driving shafts 32, and each of the upper

120 shafts 58 is provided with an additional sprocket 74, connected by the chain 76 to a sprocket 78 on a counter-shaft 80 mounted in brackets 82 on a suitable support 84, and having a sprocket 86 connected by a sprocket chain 88 to the sprocket wheel 68 on one of the shafts 58 in the lower conduit.

125 The last cooling vessel of the series is provided with a discharge pipe 92. From this discharge pipe leads a delivery pipe 94, through which the cooled distillate is delivered to a filter tank or the like. Also lead-

ing from the discharge pipe 92 is the return pipe 96 discharging into the upper end of one of the cooling vessels. In the discharge pipe 92 is a thermostat 98, comprising a tube 100 having its lower end extending into the interior of the discharge pipe and having at its upper end a pair of spaced, insulated contacts 102. In the tube is a mercury column 104. The contacts 102 are the terminals of the circuit 106 of the solenoid 108, said circuit comprising also the storage battery 110. In the delivery pipe 94 is a valve 112, and in the discharge pipe 96 is a similar valve 114. These valves are connected together and to the core 116 of the solenoid by the links 118, 120. When the temperature of the distillate in the discharge pipe 92 rises above a predetermined point, the mercury 104 will expand and bridge the opening between the contacts 102, thus completing the circuit 106 and energizing the solenoid 108, causing the core 116 to be drawn inward and thus closing the valve 112 in the delivery pipe and opening the valve 114 in the return pipe. When the temperature of the distillate falls below the predetermined point, the circuit 102 will be broken by the withdrawal of the mercury column 104 between the contacts 102, and the solenoid will be deenergized. The spring 122 will then act to move the core 116 of the solenoid and open the valve 112, at the same time closing the valve 114.

By this arrangement it will be seen, that, in case the cooling vessels fail to cool the distillate sufficiently, this distillate will be automatically returned to the cooling vessels for further treatment, and the danger of supplying the filter tank, or the like, with sufficiently cooled material is eliminated.

The above disclosure of a thermostatic control is illustrative and diagrammatic merely, and is not intended to represent an actual commercial installation. It is sufficient, however, to enable any one skilled in the art to reduce my invention to commercial form, as automatic control of the opening and closing of valves by means of thermostats is well known. In actual practice it is my intention generally to use one of the types of temperature responsive mechanisms manufactured by the Geissinger Regulator Company of New York and illustrated in their catalogues.

I have shown the return pipe as emptying into the last vessel of the series, as repassage through this vessel, in which the cooling medium is at its lowest temperature will usually be sufficient to cool the oil to the desired point. The return pipe may, however, be connected to deliver the insufficiently cooled oil at any other desired point in the system. By placing between each two cooling vessels means for positively forcing the distillate from one vessel into the other, I

am able to successfully treat comparatively heavy distillates. In fact, the machine is capable of handling paraffin in a semi-solid or "mushy" state.

From the above it will be seen that in my invention the described elements coöperate to maintain a constant flow of the distillate and the wax precipitated therefrom through the series of vessels, delivering the mixture at the desired temperature to a filter tank or the like; clogging of the system by the accumulation of wax on the walls of the vessels or by the densifying of the mass of distillate in the vessels, or in the conduits connecting them, is positively prevented. The spring pressed scrapers and the screw conveyers act on the distillate at practically every point of its path of flow to prevent the accumulation of a solid deposit in the system.

While I have described a specific form of my invention, it is to be understood that modifications may be introduced within the scope of the appended claims. It is not essential that the cooling vessels be arranged vertically; they may, if desired, be arranged horizontally. The cooling vessels may, moreover, be arranged in compact groups, rather than in a linear series. The conduits between the vessels may be fitted with other forcing means than screw conveyers. Any suitable type of thermostatically controlled mechanism for operating valves in the delivery and return pipes may be substituted for that shown. Instead of securing the scrapers 40 to a more or less yielding frame 18, I may, as shown in Figs. 7 and 8, mount them on lugs 43 secured directly to the shaft 24.

What I claim as new is:

1. In combination, a series of upright cooling vessels, a rotatable scraper frame in each vessel for scraping congealed substance from the walls of said vessels, said scraper frames and vessels being constructed to permit the free flow of material lengthwise of said vessels, a conduit between the vessels of each pair of vessels and smaller in diameter than each vessel, and means in said conduit for forcing the material to be cooled through said vessels.

2. The combination of a series of cooling vessels arranged side by side, a conduit for each pair of vessels connecting corresponding ends of said paired vessels, the conduits at the respective ends of the vessels being divided into groups located at opposite sides of the axes of said vessels, and a conveyer in each conduit.

3. The combination of a series of cooling vessels arranged side by side, a conduit for each pair of vessels connecting corresponding ends of said paired vessels, and a screw conveyer in each conduit, each of said conduits being out of axial alinement with one

of the adjacent conduits, to permit the withdrawal of each screw conveyer through the end of its conduit.

4. The combination with a cylindrical vessel, having a wall, the inner surface of which is adapted to receive a film of adhering material, of a scraper frame mounted for rotation in said vessel, a scraper pivotally mounted on said frame, its pivot extending substantially parallel with the axis of said vessel so that there is a tendency for said scraper to swing outwardly on its said pivot due to centrifugal force, a helical spring coiled about said pivot and the ends of which are engaged respectively with said frame and said scraper, whereby said scraper is positively forced outwardly about its said pivot to supplement the action of the centrifugal force in bringing its scraping edge against the said inner surface of said wall so as to adapt said scraper to remove the material adhering to said surface, and means for rotating said frame and carrying the said scraper in scraping contact with said inner surface substantially as fast as said material accumulates thereon.

5. In an oil distillate chilling machine, in combination, a plurality of cooling vessels, each vessel comprising a body portion, a head detachably mounted at each end thereof, each head having an eccentric, inwardly concave portion and a cylindrical portion communicating with said concave portion and extending laterally therefrom, with its axis crossing said head laterally of the axis of said vessel, means for securing each of said cylindrical portions to a corresponding portion on the head of an adjacent vessel to form a cylindrical conduit between said vessels, a screw conveyer for rotation in said conduit to force the contents of one vessel into the adjacent vessel.

6. In combination, a series of cooling vessels, each of said vessels comprising a cylindrical body member, a head for each end thereof, the heads at one end of each pair of vessels being joined by a cylindrical conduit member extending laterally from each head, and with its axis crossing said heads laterally of the axes of said cylindrical body members, each head being eccentrically recessed to provide a passage between said body and said head, a conveyer mounted in each conduit, a rotatable shaft extending axially of each vessel and having a central bearing in each head thereof, scrapers carried by said shaft for operating on the inner wall of said vessel, driving means

mounted on certain of said heads, and connections from said driving means to said shafts and conveyers.

7. In combination, a pair of cooling vessels, means for forcing the liquid being cooled from one vessel to the other, comprising a cylindrical conduit connecting the vessels at one end, said conduit connected to each vessel laterally of the axis thereof, a rotatable shaft extending through said conduit and removably mounted therein, a screw conveyer on said shaft and closures for the ends of said conduit removably mounted thereon to permit the removal of said conveyer and shaft.

8. In combination, a cooling vessel, a cylindrical body member, a head therefor, said head having an eccentric inwardly opening recess therein, a rotary scraper frame in said body member, a shaft on which said frame is mounted, a bearing for said shaft central of said head, and a conveyer mounted in said head laterally of said bearing.

9. A cooling vessel comprising, in combination, a vessel proper, a hollow head fixed at one end of said vessel, said head having a centrally located bearing and a cylindrical portion extending laterally at substantially a right angle to said vessel but located to one side of the longitudinal axis of said vessel, a rotary shaft coincident with said axis and provided within said vessel with a scraper to scrape off the congealed material on the inner surface of said vessel, one end of said shaft being journaled in said bearing, and a screw-conveyer rotatable in said cylindrical portion.

10. The combination of two cooling vessels, hollow heads fixed at corresponding ends of said vessels, said heads having centrally located bearings, and two abutting and connected cylindrical portions, each extending laterally from said head at substantially a right angle to its corresponding vessel but located to one side of the longitudinal axis of said vessel, a rotary shaft for each vessel coincident with said axis and provided within said vessel with a scraper to scrape off the congealed material on the inner surface of said vessel, one end of said shaft being journaled in its corresponding bearing and a screw-conveyer located to one side of the said bearings and rotatable in said connected cylindrical portions.

Signed at New York, N. Y., this 21st day of February, 1917.

ALANSON McD. GRAY.
